UNITED STATES PATENT OFFICE.

GEORGE FREDERICK BULL AND ERNEST WALTER STARKEY, OF BIRMINGHAM, ENGLAND; SAID STARKEY ASSIGNOR TO CHARLES H. PUGH LIMITED, OF BIRMINGHAM, ENGLAND.

CARBURETOR FOR INTERNAL-COMBUSTION ENGINES.

Application filed January 2, 1920. Serial No. 349,001.

To all whom it may concern:

Be it known that GEORGE FREDERICK BULL and ERNEST WALTER STARKEY, subjects of the King of Great Britain, residing at Small Heath, Birmingham, England, have invented certain new and useful Improvements in Carburetors for Internal-Combustion Engines, of which the following is a specification.

10 This invention relates to carburetors for internal combustion engines, of the kind in which air is drawn past the fuel jet through an atomizing tube situated in the main air inlet, the fuel being atomized by the air passing through the atomizing tube and mixing with the main air supply drawn through the main air inlet.

With this construction of carburetor it is found that for the lower ranges of speed 20 the mixture is too rich unless the throttle valve is provided with an opening therein especially shaped to suit the particular kind of engine with which the carburetor is associated.

25 The principal object, therefore, of the present invention is to provide means for obtaining a correct mixture for starting and slow-running without the necessity of specially shaping the throttle valve for different engines.

According to the invention, the throttle valve is provided with a slot which is arranged to come opposite the atomizing tube at small throttle openings, while the said 35 atomizing tube is provided upon the throttle side of the nozzle, with jet-damping air passages which reduce the suction on the nozzle at slow speeds, and these damping passages are situated in the constricted portion 40 of the main air intake passage of the carburetor so that at low speeds air is taken through these holes from the main air passage and reduces the suction on the nozzle, whereas when the throttle is opened the 45 effect of these damping passages is automatically cut out or suppressed without the use of any moving parts. To regulate the richness of the mixture to suit requirements the size of the damper holes is adapted to 50 be varied by means of a regulating sleeve.

Figure 1 of the accompanying drawing represents a vertical longitudinal section partly in elevation of a carburetor con-

structed in accordance with the present invention.

55

Figure 2 is an end view of the same.

Figure 3 represents a horizontal section through the atomizing tube.

Figures 4 and 5 are transverse sections through the jet damping apertures of the atomizing tube and through the regulating sleeve showing how the regulating of the mixture is effected.

60

Figure 5^a is a detail view on a larger scale, of a portion of Figure 1 showing the upper end of the fuel nozzle, the constricted portion 6 and the atomizing tube and the sleeve surrounding the latter being cut away in a vertical plane between said nozzle and the barrel valve.

65

Figure 6 is a section through a vertical type of carburetor constructed according to the present invention.

70

Figure 7 represents a cross section through the atomizing tube and regulator.

75

Figures 8 to 10 show modifications.

Referring to Figures 1 to 6, the nozzle 1 is arranged vertically and being supported by the bracket 15 carried by the float chamber 16 extends into the bore of a horizontal atomizing tube 2 which is rotatably mounted within an outer regulating sleeve 3 carried by transverse web 4 crossing the main air inlet 5, the inner ends of the atomizing tube and regulating sleeve extending into the constricted portion 6 of the air inlet passage adjacent to the barrel-type throttle valve 7. The atomizing tube 2 is provided, upon the throttle side of the nozzle, with jet-damping apertures 8, 8 adapted to be brought more or less into register with similar apertures 9, 9, in the regulating sleeve 3, said apertures being situated within the constricted portion 6. When the throttle is nearly closed the inner end of the atomizer tube is opposite a slot or slow-running aperture 10 in one side of the intake port of the barrel-type throttle valve, and remains opposite said slot throughout a range of movement, until the main area of the intake port comes opposite to said atomizer. During the initial opening stages of the throttle the depression created by the engine is practically wholly concentrated on the atomizer tube 2, whilst the flow of air in the constricted portion 6 surround-

105

partly in elevation of a carburetor con-

ing the atomizer is of low velocity, due to the depression at that point being small. Consequently air is caused to pass from the constricted portion of the main air inlet 5 passage through the damper holes 8, 9, into the atomizer tube on the engine side of the nozzle, thereby reducing the depression about the nozzle and diminishing the supply of fuel. As the throttle is opened, and the 10 speed of the engine increases, the depression in the air passage around the atomizer tube 2 becomes greater, and the flow of air through the damper holes 8, 9, is diminished, until a point is reached when the depression 15 outside the atomizer tube is equal to that within the said tube, so that no air passes through the damper holes, and consequently there is no restriction on the flow of fuel from the nozzle, which can be of large size 20 in order to supply the full quantity of fuel required with wide throttle openings, the supply being automatically reduced by the damper holes as the throttle is closed and the speed decreases.

25 To adjust the quantity of fuel delivered at low speeds for a given engine, or for a given set of conditions, the effective size of the damper holes can be increased or decreased by rotating the atomizer tube 2 within the interior of the fixed outer regulator sleeve 3, so as to cause the apertures 8, 9, to register more or less as required. The rotatable atomizer tube 2 is slotted at 30 11 to allow of the nozzle 1 passing through and has a knurled head or flange 12 at its outer end by which it can be rotated, and may be locked in its adjusted position by a spring-plunger 13 engaging the knurled periphery. Two stop pins 14, 14, determine 35 the range of adjustment. Once the richness of the mixture has been determined for a given set of conditions, it is not necessary to alter the regulator unless those conditions vary.

40 45 In the application of the invention to the vertical type of carburetor shown in Figures 6 and 7, the atomizer tube 2 is arranged vertically and is mounted upon a bracket 15 carried by the float chamber 16, said tube 2 being provided with a central vertical bore 17 for the passage of the atomizing air, and its upper end extending into the intake port of the barrel-type throttle valve 7. At a suitable point in the tube is a petrol nozzle 50 1 extending into the tube in a horizontal direction, said nozzle being screwed into a hole in the side of the atomizer so that its bore communicates with a vertical fuel passage 18 drilled through the body of the atomizer tube. At the lower end of the latter this fuel passage enters a groove 19 communicating with a passage in the carrier bracket leading from the float chamber.

55 The atomizer tube is situated within the constricted portion 6 of the intake passage,

so that when the throttle is opened a main supply of air is drawn through said air-inlet and throttle and around the atomizer. The latter is provided, above the nozzle but below the throttle, with two or other suitable number of inclined nozzle-damping air passages 8, 8, situated within the constricted portion 6 and leading therefrom to the interior of the bore. When the throttle is nearly closed the inner end of the atomizer tube 2 is opposite the slot 10 in one side of the intake port of the barrel type throttle valve 7 and remains opposite said slot throughout a range of movement, until the main area of the intake port comes opposite to said atomizer. During the initial opening stages of the throttle the depression created by the engine is practically wholly concentrated on the atomizer tube 2, whilst the flow of air in the constricted portion 6 70 75 surrounding the atomizer is of low velocity, due to the depression at that point being small. Consequently air is caused to pass from the constricted portion 6 through the damper holes 8, 9, into the atomizer tube 80 on the engine side of the jet, thereby reducing the depression about the jet and diminishing the supply of fuel. As the throttle is opened, and the speed of the engine increases, the depression in the constricted portion 6 85 90 around the atomizer tube 2 becomes greater, and the flow of air through the damper holes 8 is diminished until a point is reached when the depression outside the atomizer tube is equal to that within the said tube, so that no air passes through the damper holes, and consequently there is no 95 100 restriction on the flow of fuel from the jet, which can be of large size in order to supply the full quantity of fuel required with wide 105 throttle openings, the supply being automatically reduced by the damper holes as the throttle is closed and the speed decreases.

110 In order to regulate the richness of the mixture, the damping passages 8 in the wall of the atomizer tube may be controlled by means of a rotatable sleeve 3 surrounding said tube and having suitable openings or cut-away parts 9 corresponding to the passages 8, so that by partially rotating the sleeve into different angular positions the said damping passages may be more or less closed according to requirements. The sleeve 3 may conveniently carry an operating arm or lever 20 provided with a pointer 115 21 adapted to serve as an indicator of the degree of richness of the mixture.

120 Or, instead of a rotatable sleeve, a sliding sleeve may be employed.

125 In the modification represented in Figure 8, the vertical nozzle 1 extends through the lower open end of a vertical and concentrically-arranged atomizer tube situated within the main air intake 5 of the carburetor, its upper end extending into the 130

constricted portion 6 of the main air inlet adjacent to a barrel-type throttle valve 7. The upper portion of the tube 2, above the nozzle, is reduced in diameter, as shown, and 5 a current of air is drawn, by the engine, through the said tube and past the nozzle, serving thoroughly to break-up and atomize the fuel which issues from the nozzle, the sprayed fuel, during normal running, mixing 10 with an extra supply of air passing around the outside of the tube 2. The said atomizer tube 2 is provided with nozzle-damping apertures 8 situated within the constricted portion 6, the size of these apertures being adapted to be adjusted by means 15 of a rotatable regulating sleeve 3 having apertures 9 which can be brought more or less into register with the apertures 8.

As in the previous arrangements, when 20 the throttle valve is nearly closed the end of the tube 2 is opposite to a slot or slow-running aperture in one side of the intake port of the throttle valve, and remains opposite this slot throughout a range of movement, 25 until the main area of the intake port comes opposite to said atomizer tube. During the initial opening stages of the throttle the depression created by the engine is practically wholly concentrated on the atomizer tube, 30 whilst the flow of air in the constricted portion 6 surrounding the atomizer is of low velocity, due to the depression at that point being small. Consequently air is caused to pass from the constricted portion 6 through 35 the damper holes 8 into the atomizer tube on the engine side of the nozzle, thereby reducing the depression about the nozzle and diminishing the supply of fuel. As the throttle is opened and the speed of the engine increases, the depression in the constricted air 40 passage around the atomizer tube 2 becomes greater, and the flow of air through the damper holes 8 is diminished, until a point is reached when the depression outside the 45 atomizer tube is equal to that within said tube, so that no air passes through the damper holes, and consequently there is no restriction on the flow of fuel from the nozzle.

50 In the modifications of the invention represented in Figures 9 and 10 the operation in so far as the throttle valve and the dampening apertures 8 are concerned is identical with that of the forms shown in Figure 8 and in the previously described modifications. In each of said figures the lower end 55 of the atomizer tube is shown as being closed by the liquid fuel nozzle 1 so that other provision must be made for the normal admission of atomizing air of the atomizer tube. This is accomplished by the ports 19 which provide communication between the interior of the atomizer tube and with the main air inlet tube opening into the latter at

65 a point where it is more or less unrestricted and therefore being not subject to the dampening effect of the throttle valve, in certain positions as are the dampening apertures 8. The distinction between figures 9 and 10 lies in the disclosure of the former figure. 70 The atomizing air inlet apertures 19 are placed some distance back of the mouth of the nozzle 1, while in Figure 10 they are shown about flush with the end of said nozzle. In both figures an external sleeve 3 75 surrounds the atomizer tube having apertures 9 and 20 aligning respectively with the dampening and atomizing air in the apertures, and by means of which the effect of area of both said apertures may be varied at 80 will by turning the sleeve 3. The effect of this adjustment upon the atomizing air in the apertures is to give a richer or leaner mixture over a whole range of throttle openings. 85

Having fully described our invention, what we desire to claim and secure by Letters Patent is:—

1. A carburetor comprising main and atomizing air tubes, communicating with the 90 fuel intake of an internal combustion engine, a liquid fuel nozzle opening into said atomizing air tube, a throttle valve controlling the communication of said air tubes with said engine intake, said throttle valve 95 being provided with ports so disposed as, in one position of the valve, to close the main air tube leaving the atomizing air tube open to the engine intake, and in another position of said valve, to leave both tubes open 100 to the engine intake, and nozzle dampening air passages in the wall of said atomizing air tube between the nozzle and throttle valve and communicating with the main air tube. 105

2. A carburetor comprising a main air-inlet having a constricted part, a rotatable atomizing tube in the main air-inlet, a throttle valve having a slot which comes opposite the atomizing tube at small throttle 110 openings, a fuel nozzle extending into the atomizing tube, and an outer fixed sleeve supporting the atomizing tube, said atomizing tube having nozzle damping apertures situated between the jet and the throttle 115 and in the constricted part of the main air-inlet, and the outer sleeve having apertures adapted to be brought more or less into register with the nozzle-damping apertures.

In testimony whereof we have hereunto 120 set our hands in presence of two subscribing witnesses.

GEORGE FREDERICK BULL.
ERNEST WALTER STARKEY.
